(57) **CLAIM**

The ornamental design for a stethoscope restraint, as shown and described.

DESCRIPTION

FIG. 1 is a perspective view of a stethoscope restraint showing my new design;

FIG. 2 is a front view thereof;

FIG. 3 is a back view thereof;

FIG. 4 is a top view, the bottom view being a mirror image thereof; and,

FIG. 5 is a right side view, the left side view being a mirror image thereof.

The broken lines immediately adjacent the shaded areas represent the bounds of the claimed design while all other broken lines are directed to environment and are for illustrative purposes only; the broken lines form no part of the claimed design.
